UNITED STATES PATENT OFFICE.

WILLIAM ARTHUR DONALDSON, OF BROOKLYN, NEW YORK.

APPARATUS FOR GRINDING AND POLISHING PRECIOUS STONES.

Application filed May 7, 1923. Serial No. 637,238.

This invention relates to apparatus for grinding and polishing precious stones, having reference particularly to improved means for supporting and adjusting a stone-carrying dop in proper correlation with a lap.

The invention has for an object the provision of means for accurately placing and holding a precious stone over the horizontal plane surface of the lap at various angles to its axis; a further object being to provide means for accurately gaging the adjustments for the production of facets of uniform angles and widths.

In carrying out my invention, I employ a bracket comprising a standard or tang having a horizontally extended arm, and a rotatable, vertically adjustable spindle extended through the free end of said arm and having an elongated head, a slide horizontally adjustable on said head, a swingingly mounted dop holder carried by said slide and comprising two members in turnably adjustable correlation with each other, means connecting said head with said dop holder, whereby longitudinal movement of said slide automatically swings the dop holder, and gage means for indicating the movements of said parts, and other novel features hereinafter fully described and specifically set forth in the appended claims.

In the accompanying drawings forming part of this specification, Figure 1 is a plan view illustrating an embodiment of my invention.

Fig. 2 is a side view;

Fig. 3 is a vertical sectional view taken on the line 3-3 of Fig. 2;

Fig. 4 is a fragmentary sectional view taken on the same line and drawn on an enlarged scale;

Fig. 5 is a fragmentary side view;

Fig. 6 is a plan view of a detail of the device; and

Fig. 7 is a sectional view of a fragment of the dop.

In the drawings, 1 indicates the bracket, which embodies an arched standard 2 and a horizontal arm 3, said bracket being adapted to be adjustably mounted on a table 5 adjacent a lap indicated by 6. The standard arm 2 is provided with the usual horizontally disposed rod 7 held against lateral displacement by abutting against a vertical pin 8 forming part of an adjustable plate 10, said plate having a slot 11 through which extends a bolt 12 which is fixed to the table 5, a

thumb-nut 13 being employed for maintaining the plate 10 in set relation. A pin 9 is also provided for lateral bearing relation with the arm 3, and a slidable sleeve 13 is mounted on said pin and is provided with a bearing-ledge 14 for supporting the forward end of the arm 3 and maintaining said arm in level horizontal position, said sleeve adapted to be maintained in set position by means of a set-screw 15.

In vertically adjustable connection with the forward or free end of the arm 3 is a screw-sleeve 16 which is in threaded relation through said free end and is adapted to be held in arbitrarily set position by means of a lock-nut 17.

Through the sleeve 16 extends a spindle 18 which is adapted to be turned independently of the sleeve 16 and held in set relation thereto by means of a nut 19 which is in screw-threaded engagement with the upper end of the spindle 18, washers 19^a being employed for bearing relation between the upper end of the sleeve 16 and said nut.

Formed integral with the spindle 18 is a head embodying the circular member 20 and longitudinally elongated guide-plate 21 having on its under surface a dovetailed tongue 22 for engaging a dovetailed groove of a slide 23 which is longitudinally adjustable by means of a screw 24 which is threaded through said slide, said screw being in turnable bearing relation with a lug 21^a of the guide-plate 21.

Swingingly engaging the slide 23, by means of a pivot 25, is the dop holder comprising the upper section 26 and lower section 27, said sections being coupled by means of a screw 28 having a head 28^a which snugly fits within a recess 27^a of the section 27. The sections 26 and 27 have interlocking teeth, shown at *a*, Figs. 2 and 5 of the drawings, and they are maintained in yieldingly coupled relation by means of a helical spring 29 placed between the head 28^a of the screw 28 and the inner end surface of the recess 27^a, whereby when the section 27 is turned around the axis of the screw 28 the same is slidably movable on the head 28^a.

Communicating with the recess 27^a is a recess 27^b for the accommodation of a dop 30, said dop having a recess 30^a for receiving a precious stone, as 31, said stone being held in place by means of a claw 32 mounted on the lower end of a slidably adjustable pin 33 which passes through a bearing 26^a.

formed integral with the section 26 of the dop holder, a set screw 34 being employed for holding said pin in properly set relation.

The dop 30 is longitudinally split, as shown at *b*, Fig. 4 of the drawings thus the diameter of the opening of the recess 30^a may be slightly varied by means of a set-screw 35, whereby in conjunction with the claw 32 the stone may be held in securely fixed relation, and the dop is held against liability of accidental displacement by means of a screw 36 which passes radially through the section 26 of the dop holder and engages said dop.

As a means for providing a bearing for the outer flat face of the stone when the same is placed inwardly, I employ an adjustable screw 37, see Fig. 7 of the drawings, which is in threaded engagement with a bushing 39 set within the recess 30^a.

Connecting the upper section 26 of the dop holder with the guide-plate 21 of the spindle 18, are swinging connecting rods 40, whereby when the slide 23 is moved in the direction of the arrow *c*, Fig. 5 of the drawings, the dop is swung in the opposite direction.

A zero mark 41 is provided on one side of the plate 21 which registers with a similar mark 42, on the slide 23, when the dop is positioned at right angles to the horizontal surface of said plate, and a calibrated scale 43 is provided for registration with the mark 42, whereby the dop may be set at a desirable degree in relation to the axis of the spindle 18.

The peripheral surface of the dop holder section 26 is provisioned with a zero point for registration with a peripheral scale 44, whereby the dop may be turned and set for producing facets of the required width, the spring 29 admitting of turnable movement of the section 27 on the section 26, but holding the sections 26 and 27 against turnable movement during the grinding and polishing process.

In the operation and use of this invention it is manifest that owing to the novel correlation of the several parts and the simple indicator means acting in conjunction therewith, an operator may very accurately gage his work for the production of facets of equal widths and uniform angles.

Having thus described my invention what I claim as new and desire to secure by Letters Patent, is:

1. In an apparatus for grinding and polishing precious stones, in combination with a bracket adapted for extension over a lap, a rotatable and vertically adjustable spindle having a head embodying an elongated guide, a slide horizontally adjustable on said guide, a swinging dop holder, and means connecting said dop holder with said guide whereby movement of said slide automatically swings the dop holder.

2. In an apparatus for grinding and polishing precious stones, in combination with a bracket adapted for extension over a lap, a rotatable and vertically adjustable spindle having a head embodying an elongated guide, a slide horizontally adjustable on said guide, a swinging dop holder comprising two sections, the lower section having means for fastening a dop, and means for connecting said dop holder with said guide whereby movement of said slide automatically swings the dop holder.

3. In an apparatus for grinding and polishing precious stones, in combination with a bracket adapted for extension over a lap, a rotatable and vertically adjustable spindle having a head embodying a horizontal guide, a slide horizontally adjustable on said guide, a swinging dop holder comprising two sections, one rotatable on the other, means yieldingly connecting said sections, and means connecting a dop to the lower one of said sections, and a yoke for connecting said dop holder with said guide whereby movement of the slide swings the dop holder.

4. In an apparatus for grinding and polishing precious stones, a vertical spindle having an elongated horizontal part on its head constituting a guide and a slide horizontally movable on said guide, and a swinging dop holder pivoted to said slide, said guide having a scale whose graduations radiate from the pivot of said dop holder, said dop holder having a pointer for registration over said scale, and means connecting said dop holder with said guide whereby movement of the slide automatically swings said dop holder.

4. In an apparatus for grinding and polishing precious stones, a vertical spindle having an elongated horizontal part on its head constituting a guide and a slide horizontally movable on said guide, and a swinging dop holder pivoted to said slide, said dop holder comprising two sections in yieldingly rotatable connection with each other, said sections having interlocking teeth, one of said sections having an annular scale and the other having an indicator mark registering with said scale, the turnable section having means for fastening a dop.

Signed at New York in the county of New York and State of New York this 28th day of April A. D. 1923.

WILLIAM ARTHUR DONALDSON.
